Fig. 4

Fig. 6

FIG. 1 is a top plan view of a hanger for culinary covers or the like embodying our new design.

FIG. 2 is a front elevational view.

FIG. 3 is a bottom plan view.

FIG. 4 is a side elevational view.

FIG. 5 is a cross-sectional view in elevation taken along line 5—5 of FIG. 1.

FIG. 6 is an elevational view thereof with a fragmentary portion of a shelf and a culinary cover shown in broken lines for illustrative purposes only.

We claim:

The ornamental design for a hanger for culinary covers or the like, as shown and described.
